UNITED STATES PATENT OFFICE.

WALTER F. ADAMS, OF LOS ANGELES, CALIFORNIA.

HIGH AND LOW SPEED WRENCH.

1,409,510.

Specification of Letters Patent. Patented Mar. 14, 1922.

Application filed April 18, 1921. Serial No. 462,094.

To all whom it may concern:

Be it known that I, WALTER F. ADAMS, a citizen of the United States, residing at Los Angeles, in the county of Los Angeles and

5 State of California, have invented a new and useful High and Low Speed Wrench, of which the following is a specification.

This invention is applicable to wrenches of various kinds including socket wrenches, 10 screw drivers and braces for operating bits of various kinds, and the principle of the invention applies more particularly to the construction of the handle for turning the tool tip which is to engage the object to be 15 wrenched, as a nut on a bolt, a head of a bolt, a head of a screw or the shank of a tool such as an auger or any other form of bit.

In operating a wrench for revolving objects such as screws, nuts, bolts, etc. which 20 have to be turned round and round on the axis by a wrench as a socket wrench or a screw driver or other device of a like character, considerable power is usually required 25 at the beginning of the operation of loosening the parts or at the close of the operation of tightening the parts, and an object of this invention is to provide a practical wrench brace device by which long leverage 30 with low speed is applied through one part 35 of the appliance when considerable force is required as in seating and starting nuts, and for starting and inserting heavy screws, and high speed with small leverage is available through another part of the operation.

The invention is broadly new, basic and pioneer in that I provide a wrench handle practically operable after the fashion of a brace and bit, comprising an engaging end 40 and a stationed handle co-axial therewith connected through two handles that are eccentric to the axis of the stationed handle and of different radii relative to each other so that when power is required, the handle 45 of longer radius can be used, and when high speed of revolution is desired the eccentric handle of lesser radius is employed.

An object and advantage is, greater facility and speed for loosening and tightening 50 elements that are capable of being loosened and tightened by rotation on an axis.

Other objects, advantages and features of invention may appear from the accompanying drawing, the subjoined detail description and the appended claims.

The accompanying drawing illustrates the invention.

Figure 1 is a view of the invention applied to a conventional brace. 60

Fig. 2 is a view analogous to Fig. 1, showing the invention as applied in a simpler form.

Fig. 3 is a fragmental view showing the end of the socket wrench illustrated in 65 Fig. 2.

Fig. 4 is a fragmental view of a screw driver tip which may be employed with a handle constructed in accordance with the form shown in Fig. 2. 70

The stationed handle 1 may be of any desirable form and is shown as a knob which may or may not be swiveled on the axially extending handle tip 2 of the appliance. 75 3 is the axially extended tool tip or terminal of said handle; said terminal may have any desired form of tip as the chuck 4, socket wrench 5 or the screw driver 6. Between the handle tip 2 and the tool tip 3, the handle is provided with two eccentric handles 80 7 and 8 connected to said tips and to each other by the radius arms 9 and 10 and the intermediate limb 11, so that when the stationed handle 1 is held in position and the wrenching device is engaged with the object to be turned; if considerable power is required for turning the wrenching device, as at the starting of a nut or bolt or the starting of a screw which has been tightly 85 screwed home, or the final setting of a nut, 90 bolt or screw; the wrenching operation may be effected by using the eccentric handle 8 of greater radius; and when it is desired to spin the nut, bolt or screw for rapid removal or tightening, the handle 7 of less 95 radius may be used.

In practical operation the handle will be held after the manner of the ordinary brace and bit; the knob or stationed axial handle 1 being held true, with the tool engaging the 100 nut, screw or other part to be revolved. The tool may be turned slowly and with great power by grasping the high power handle 8 and swinging it around and around as with the use of an ordinary brace and bit. 105

When it is feasible to spin or rapidly revolve the element being turned, the high speed handle 7 of shorter radius is revolved. This can be done with high speed, thus greatly facilitating the work. 110

The axes of the eccentric handles are parallel to the axis of the tips 2 and 3 of said

appliance. Both radius arms 9 and 10 preferably are located on the same side of the axis of the tips 2 and 3 and the handle 7 of shorter radius is between the stationed handle 1 and the handle 8 of greater radius, so that in practical use the handle of less radius does not interfere with the operation of the handle of greater radius.

The eccentric handles 7 and 8 may or may 10 not be provided with grips 7' and 8' journaled thereon.

By mounting both handles on the same side of the unitary axis of the tips 2 and 3, the tool is given a practical condensed form 15 and is very simple in construction and operation.

I claim:

1. A wrench handle comprising two coaxial tips and intermediate eccentric handles, the axes of which are parallel to the axis of the tips; said parallel handles being connected together and with the tips by radius arms of different lengths.

2. A wrench handle comprising a tool tip at one end and an axial handle coaxial therewith, and two eccentric handles connected to each other and to the tool tip by radius arms of different lengths; the radius of the handle next to the tool tip being greater than the radius of the eccentric handle next to the 30 axial handle.

3. An axially revolvable wrench having coaxial tips and eccentric handles of different radii on the same side of the axis of said tips.

4. A revolving wrench having two coaxial tips and a plurality of intermediate eccentric handles having radii of different length, and connected to said tips by radius arms.

In testimony whereof, I have hereunto set my hand at Los Angeles, California, this 9th day of April, 1921.

WALTER F. ADAMS.
